MACHINE AND METHOD FOR MIXING FIBERS

Oliver A. Benoit, Lawrence, Mass.

Application March 11, 1931. Serial No. 521,803

4 Claims. (Cl. 19—146)

This invention relates to machines and processes of mixing textile fibers.

In manufacturing fibers into yarn, woven material, knit goods or bats of felting, it is desirable that the resulting material should have the same consistency and in many cases the same color whether on the first day of the mix or on the last day.

This invention is particularly useful in mixing fibers of wool, cotton or similar material.

In the manufacture of woolen and worsted cloth, different grades of wool are used and particularly different colors of wool fibers and sometimes cotton and wool are used to make a predetermined blend and it is especially desirable that all yarn or cloth which is supposed to be of a certain consistency, color mixture or both should be the same at all times.

In order to understand this device accurately, it will be necessary to consider that the usual way of mixing wool is as follows:

In a bin perhaps fifteen to twenty feet square, from five to ten thousand pounds of wool is placed by hand by several workmen.

The total quantity, for instance, of each color is weighed out and then each color is spread in a layer, then another color etc. until all of it is in place.

Such a bed is usually located directly in front of a mixing picker and this mixing picker is idle while the bed is being laid. When the bed is laid, the picker is started and an operator picks up an armful of the stock endeavoring to pick it up edgewise, usually with not much success, and dumps this into the hopper of the picker.

Such a mixing picker mixes the stock fed to it reasonably well, but it is obvious that there are no two armfuls of stock which contain the right proportion of each kind or color of stock, as it is all done by guess work, and when one armful has been taken, the stock tends to fall into the resulting hole so that different armfuls contain different proportions of stock.

The purpose of this invention is accomplished by handling the stock in batches or masses of a convenient size for one operator. Each batch or mass is built up by placing layers of stock horizontally in the desired proportions and advancing each of these small masses, after it is laid, endwise to devices which will remove the stock by continuously combing or hooking it off, taking off an equal amount in thickness from each layer all the time so that the stock which is carried along is uniform from time to time, and then delivering it to stirring or mixing

devices which constantly and continuously agitate it or stir it so that a thorough mixing is secured.

Each successive layered mass should be of substantially the same size, and of rectangular parallelepiped form and each layer should be of the same length and width, but the various layers in the same mass may be of different thicknesses. The layers should be stacked in vertical alinement one directly above or below its neighbor.

In the drawings, Fig. 1 is a diagrammatic side elevation partly in section of the device in operation.

Fig. 2 is a plan view of Fig. 1.

Fig. 3 is an elevation showing the front of the weight indicator dial.

Fig. 4 is an elevation partly in section as from the right of Fig. 1.

Fig. 5 is an enlarged detail end view of the receiving box.

Fig. 6 is an enlarged detail back view of one end of the receiving box.

Fig. 7 is a diagram showing part of the drive mechanism.

In the drawings, A represents the floor as of a factory in which is a longitudinal rectangular pit 10 over part of which is a floor 12 which serves as a platform on which an operator such as O can stand. 11 represents the ceiling and 13 the regular top of the floor.

W represents a weighing device which includes a receiving box 20 shown as having a flat hinged dump bottom 21 held in place by a latch L and having also closing means 45 by which it can be closed after it has been opened to dump the contents.

Box 20 is shown as being steadied by guides 24 and suspended by rods 25 from levers 26, 26 pivoted to hangers 27, 27 by being fixed to a rod 126 which carries an arm 28 which engages one end of another scale bar 29 the other end of which is connected to a rod 90 which enters an indicator 91 having a dial 92 around which are the usual visible weight marks 93 running from one to one hundred and the movable weight signals 94, 94, 94 which can be moved around and put in such places as desired. See Fig. 3.

These may be colored, for instance, to indicate red, blue, black, etc. and the dial is in such position that the operator O has it directly in front of him at all times.

96 is a pointer of any usual type which moves around the visible weight marks indicating the weight in box 20.

C indicates conveyer mechanism as a whole and

110

includes a horizontal apron 30 which forms the bottom of a chute having sides 100 and 101 and travels around rolls 31, 31, one end of apron 30 being under receiving box 20.

5 33 is a spiked lifting apron which extends down proximate the end of the horizontal apron 30 which is not under box 20 said lifting apron extending over the roller 34 at the bottom and 35 at the upper end of an enclosed casing 36.

10 37 is a comb of well known type such as used in many wool feeding devices and S indicates stripping mechanism which may be a brush roller the function of which is to remove stock from the upper end of the lifting apron and to deliver 15 it to any of the well known types of mixing pickers indicated by M.

This picker M rests on the floor A and has a horizontal feed apron 50 which receives the stock from stripping mechanism S and carries it along 20 through the beaters inside of casing 51. These beaters amount to stirring means which agitate the stock received from apron 50 thereby mixing it as it comes along and 52 represents delivery means for clearing picker M shown as a fan 53 and pipe 54 which pipe may extend to a receiving 25 bin in any suitable position.

The various kinds of stock are indicated by the letters R, B, G and P and the batches or different positions of the stock by the numbers 30 1, and 2.

The operator O stands next to the receiving box 20 and the trucks T, T, T, T, each preferably containing wool of a different color such as red, blue, green or purple or of different quality 35 are pushed up so that he can easily reach into each one for the color desired.

The dial 92 may have the visible weight marks 39 running around from one to one hundred pounds and the weight signals such as 94 are 40 moved into position as 20 for red, 15 for blue, 35 green and 30 purple, the later being at the 100 mark.

The operator takes from the red truck handfuls of stock which he drops into the box 20 45 until the pointer reaches the red signal after which he starts with the blue as far as the blue signal, then green and purple until the total of one hundred pounds is reached.

Each color is spread in layers as evenly as reasonably possible, the box 20 being perhaps four feet wide and eight feet long and of a convenient depth to hold perhaps one hundred pounds of wool.

If the one batch was dumped before the preceding batch or mass had been moved by the horizontal conveyer apron 30 out from under, there would be an overlapping and undesirable piling of the stock.

To avoid this, there is preferably provided 60 locking and unlocking mechanism for a latch for the dump bottom 21 which cannot be released until the first batch such as that marked 1 in the drawings has got clear away from under the second batch marked 2.

65 As shown, the receiving box 20 has a flat dump bottom 21 which can be held up by what I will call a latch L through the medium of ropes 42, 42 which pass over loose pulleys 43 one at each end of box 20.

70 The bottom 21 is shown as two doors of equal size each hinged one at the front and the other at the back of the long side of box 20.

The ropes 42 after passing over pulleys such as 43 are wound as upon barrels 44, 44 carried 75 at each end by a shaft 144 at each end of which

is a hand wheel 45, 45 by which the doors can be closed.

46 is a ratchet fixed on shaft 144 which engages a pawl or handle 47 which can be manually released when not locked by the latch locking 80 mechanism which will be now described.

The latch may be considered as including the pawl and ratchet while the ropes, barrels and hand wheel may be considered part of the latch or merely as the mechanism for closing the 85 bottom of the box.

128 is a plunger normally pushed forward by a spring 49 so as to pass back to the handle of pawl 47 whereby it cannot be manually opened.

This plunger 128, however, is controlled by a 90 solenoid 48 which connects by suitable conducting wires 40 and 41 with a switch 141 carried at the end of the swinging arm 140. This swinging arm is carried by a bracket 142 fastened under the floor 12 in such position that it will slide 95 over the top of a mass of fibers such as 1 or 2 as that mass is carried along by the horizontal apron 30 thereby through switch 141 keeping open the circuit through the wires 40 and 41 and solenoid 48, thus preventing the latch from being 100 operated to dump box 20.

However, when the arm 140 drops to the vertical position as shown by the dotted lines in Fig. 6, the electric circuit is closed, the solenoid withdraws the plunger 128 and the operator 105 can then unlock the latch and allow the mass of fiber in the box 20 to be dropped on apron 30.

This apron 30 normally may move perhaps one foot a minute while the lifting apron 33 may travel one hundred fifty feet a minute and the 110 mechanism of the picker and blower may travel still faster.

The driving mechanism shown is substantially as follows:

The shaft 60 has a pulley 61 which by means 115 of belt 62 drives another pulley 63 for the fan 53. Pulley 65 also carried by shaft 60 drives a belt 66 which engages the pulley 67 on shaft 68 which shaft drives the picker.

A small pulley 69 on shaft 68 through a belt 70 120 drives another pulley 71 on shaft 72.

Shaft 72 carries a large gear 73 which engages a smaller gear 74 on a counter shaft 174 which carries a sprocket 75 which by means of a chain 76 drives another sprocket 77 on a shaft 78 which 125 carries the bottom roller 34 of the lifting apron.

Shaft 78 carries a small pulley 178 which through belt 80 drives a very large pulley 81 which is revoluble with a small pulley 181 and this small pulley 181 by means of belt 182 drives 130 another large pulley 82 which revolves with a small pulley 183 which drives a belt 83 which belt drives another pulley 84 revoluble with roller 31 for the horizontal apron.

The stripping roller S which cleans stock from 135 the lifting apron 33 is shown as driven by a belt 136 which extends from a large pulley 135 on top roller 35 to a small roller 137 on the shaft of roller S.

The mixing picker can be omitted and the spiked 140 lifting apron 33 of the conveyor mechanism can deliver the stock which it combs or pulls off of each horizontally layered mass to any other mixing device or into a bin.

The main idea is to form the small layered 145 masses and to then successively comb or pull the stock from the ends.

The stock for each layer could be weighed in any sort of scale and the masses could be formed directly on the horizontal apron by building up 150

- Layers while it was stopped. It would not be practical to build such layers to form rectangular parallelepiped blocks while the apron was in motion.
- 5 In building such masses on a stationary apron, some sort of form must be used to keep the layers one on top of the other and of uniform length and width. Massed layers with the use of suitable forms could be built on a horizontal apron while it was stopped and the apron could then be started up, but this would reduce production.
- 10 By my process, the apron is constantly moving, each mass being built up while stationary and then being dumped or transferred to a constantly moving apron.
- 15 The masses might be built up by weighing the stock for each layer and then spreading the layers one on top of the other in a rectangular truck, such for instance as shown at T or in a box of rectangular parallelepiped form, and then tipping the truck or box thus dumping the whole mass on the constantly moving horizontal apron or conveyor. Each mass should be carefully dumped in line with the preceding or succeeding mass, but no time would be lost as the line of masses would be advancing all the time and the spiked lifting apron would be constantly cutting off the end of each mass as it was presented, whereby small vertical continuous sheets alternately of the different stocks of the different layers would be carried along and delivered to a suitable mixing picker or receiving bin.
- 20 I claim:
1. In a machine for mixing fibers; the combination of a weighing device including a receiving box having a dump bottom, a latch to hold the bottom in receiving position and a weight indicator with fixed visible weight marks, movable weight signals, and a pointer; with conveyor mechanism including a horizontal apron one end of which extends under the receiving box, and a spiked lifting apron proximate the other end of the horizontal apron and which extends up over and is adapted to deliver stock to a mixing picker; said mixing picker which includes stirring means and means to discharge stock therefrom; and means to drive the conveyor mechanism and the mixing picker at predetermined speeds.
- 25 2. In a machine for mixing fibers; the combination of a weighing device including a receiving box having a dump bottom, and a weight indicator with fixed visible weight marks, movable weight signals, and a pointer; with conveyor mechanism including a horizontal apron one end of which extends under the receiving box, and a spiked lifting apron proximate the other end of the horizontal apron and which extends up over and is adapted to deliver stock to a mixing picker; said mixing picker which includes stirring means and means to discharge stock therefrom; and means to drive the conveyor mechanism and the mixing picker at predetermined speeds.
- 30 3. The process of mixing fibers which consists of successively forming masses of fibers in substantially the same place, each mass being of substantially the same size and material and being built up by placing the stock in layers of substantially the same width and length, each layer being of stock of somewhat different characteristics from the adjoining layers and each layer being of substantially the same thickness through its width and length, and of successively advancing such layered masses one after the other horizontally to a predetermined position and there continuously removing the end of each mass as it advances; and of then stirring the fibers removed from each mass.
- 35 4. The process of mixing fibers which consists of successively forming stationary masses of fibers of substantially rectangular parallelepiped form, each mass being of substantially the same size and material and being built up by placing the stock in layers of substantially the same width and length, each layer being of stock of somewhat different characteristics from the adjoining layers and each layer being of substantially the same thickness through its width and length, and of successively moving each mass to a new location in alignment with another similar mass and advancing such layered masses one after the other horizontally to a predetermined position and there continuously removing the end of each mass as it advances; and of then stirring the fibers removed from each mass.
